UNITED STATES PATENT OFFICE.

JOHN WILLIAM KINCANNON, OF DYERVILLE, CALIFORNIA.

VIOLIN.

1,413,916.

Specification of Letters Patent. Patented Apr. 25, 1922.

Application filed May 12, 1919. Serial No. 296,573.

To all whom it may concern:

Be it known that I, JOHN WILLIAM KINCANNON, a citizen of the United States, residing at Dyerville, in the county of Humboldt and State of California, have invented a new and useful Violin, of which the following is specification.

The present invention relates to violins, the object of the invention being to provide 10 a violin wherein the tone will be rendered louder and clearer and which will generally improve the harmony of the instrument.

A further object of the invention is to improve violin construction in general and to 15 render the same simple and efficient in use.

Still another important object of the invention is to provide a violin construction, the belly of which is prevented from sagging in or warping which would detract from the 20 sound qualities of the violin.

Still another object of the invention is to provide a violin wherein the musical tones are rendered more audible than in the ordinary violin and which is just as simple in its 25 mechanical make-up.

An additional object is to provide a violin having the above characteristics, which is simple in construction, which consists of few parts and may be readily assembled and dis- 30 assembled, and which may be manufactured and placed on the market at a minimum cost.

With the above and other objects and advantages in mind, the invention consists in the combinations of elements, arrangements 35 of parts, formations and constructions, and the general assemblage, the details of which will be hereinafter specifically referred to and illustrated in the accompanying drawings, the inventive features being explicitly 40 recited in the appended claims.

On the drawings: —

Figure 1 is a plan view partly broken away and in section, showing a violin constructed in accordance with my invention;

Figure 2 is a side elevation or edge view of the device, partly broken away and in section;

Figure 3 is a sectional view taken on the line 3—3 of Figure 1 and looking in the direction of the arrows.

Referring specifically to the drawings, wherein like characters of reference designate like parts in all of the views, the numeral 5 denotes the violin body which is of 55 the usual construction, except that the usual sound openings or ports in the top are omit-

ted, and said body is provided with openings 6 at opposite sides to permit the sound to escape therethrough. While the ordinary body is pressed upwardly and downwardly 60 at the belly and back respectively, and provided with f-openings at the belly, it is to be understood that in the present instance the top or belly and the back or bottom are preferably flat but may be otherwise suitably 65 constructed or shaped.

Extended transversely in the body 5 at a point which would be beneath the bridge of the violin is a cross bar 10 which has its ends beveled and glued or otherwise secured to 70 the opposite sides of the body and supported above the bottom of the body by blocks or braces 11 secured to the body in any suitable manner. The cross bar 10 is formed with an upstanding projection 12 which bears 75 against the belly 13 which is secured to the body in the usual manner.

The principal part of the invention is the equalizing bar 14 which is positioned upon the inner face of the belly edgewise and extends diagonally across the same or obliquely with respect to the longitudinal axis of the belly. The lower longitudinal edge of the equalizing bar is curved from its opposite ends so that the widest part of the bar is disposed directly below that part of the violin 80 strings above which the bow is moved by the player. This causes some of the sound vibration to travel towards the opposite ends of the belly.

It should also be noted that the cross bar 10 is disposed at a point to lie beneath or substantially beneath the bridge of the violin and the upstanding projection 12 engages the top or belly of the body 5 to one side of 95 the longitudinal and transverse centers thereof. The equalizing bar 14 intersects the transverse bar at a point which is the same distance from the opposite side of the longitudinal center as the distance between said center and the projection, or the projection is distanced or spaced from said center at the opposite side. By arranging the bar 14 diagonally within the body it serves to reinforce the instrument directly under the 100 strings as well as to assist in the transmission of vibrations laterally with respect to the longitudinal axis of the body.

The embodiment of the invention herein shown and described is considered the preferred construction but it will be understood that the same is subject to various changes 110

and modifications, and that I reserve the right to make such changes and modifications which I may be fairly entitled to in accordance with the appended claims.

5. What I claim as new and desire to secure Letters Patent on, is:—

1. The combination with a violin body having openings in its opposite sides, of a bar extending transversely across the violin 10 and engaging the sides thereof, blocks supporting said bar, an upstanding projection formed on the bar and engaging the belly, and a bar secured to the under face of the belly and disposed obliquely with respect 15 to the longitudinal axis of the same.

2. A violin comprising a body having perforated sides, a belly and a bottom portion, a bar extending transversely within the body

and supported at its ends adjacent the sides of the body, said bar having an upstanding 20 projection engaging the belly to one side of the longitudinal center thereof, and a bar secured to the under face of the belly and disposed obliquely with respect to the longitudinal axis, said oblique bar intersecting the 25 transverse bar at a point the same distance from the opposite side of the longitudinal center as the distance between said center and the projection.

In testimony that I claim the foregoing 30 as my own, I have hereto affixed my signature in the presence of two witnesses.

JOHN WILLIAM KINCANNON.
